[57] CLAIM

The ornamental design for a hinge shim plate, as shown and described.

DESCRIPTION

FIG. 1 is a perspective view of a hinge shim plate embodying my new design;

FIG. 2 is a left side view thereof;

FIG. 3 is a front view thereof, the rear being a mirror image;

FIG. 4 is a right side view thereof;

FIG. 5 is a top view thereof; and

FIG. 6 is a bottom view thereof.
